UNITED STATES PATENT OFFICE.

WILLIAM A. CECIL, OF EVANSVILLE, INDIANA, ASSIGNOR OF ONE-HALF TO ROBERT R. WILLIAMS, OF EVANSVILLE, INDIANA.

WOOD-IMPREGNATING APPARATUS.

1,178,132.

Specification of Letters Patent.

Patented Apr. 4, 1916.

Application filed May 28, 1914. Serial No. 841,564.

To all whom it may concern:

Be it known that I, WILLIAM A. CECIL, a citizen of the United States, residing at Evansville, in the county of Vanderburgh and State of Indiana, have invented certain new and useful Improvements in Wood-Impregnating Apparatus, of which the following is a specification.

An object of my invention is to provide an apparatus so constructed that a mixture or emulsion of oils or oil and solutions immiscible therewith may be introduced into the impregnating chamber and will be maintained a perfect mixture or emulsion during the period of absorption or penetration.

A further object is to accomplish a constant and more or less rapid circulation and passing of the impregnating mixture or emulsion from the liquid supply tank into the impregnating tank or cylinder and back again to the supply tank, and thus maintain a fresh supply of impregnating fluid in the cylinder at all times.

Yet another object is to prevent the stoppage or plugging of the cells and pores of the wood with carbon or any suspended matter that may be in the oil solution, this being accomplished through holding the matter suspended and causing the same to be moved away from the entrance to the pores or cells of the wood by maintaining the constant circulation of the preservative fluid in the impregnating cylinder during the period of penetration.

A still further object is to provide an apparatus in which the impregnating fluid is maintained and operated under pressure during the penetrating process and the air driven from the cells of the wood by the penetration of the impregnating fluid into the pores thereof is permitted to escape without reducing the pressure of the liquid within the impregnating cylinder, or in any way disintegrating or disturbing the homogeneity of the liquid contained within this cylinder.

With other objects in view, which will be referred to, my invention consists in the peculiar combination and novel arrangement of parts, such as will be hereinafter more fully described in connection with the accompanying drawings and more particularly pointed out in the appended claims.

In the drawings:—Figure 1 is a schematic

view in side elevation to illustrate the general arrangement of the parts of my apparatus. Fig. 2 is a longitudinal vertical sectional view through the impregnating cylinder and the liquid supply tank as disclosed in Fig. 1. Fig. 3 is an enlarged detail sectional view to better illustrate the structure of the automatic pressure valve.

In the present processes for the preservative treatment of railroad cross-ties, piling, lumber and other forest products, by impregnating the pores or cells of wood with a preservative liquid or liquid compound, a more uniform penetration and better preservative treatment, especially of the dense and close grained timber is accomplished when the liquid is circulated over and around each piece of wood during the time of impregnation. When the impregnating liquid is an admixture of two or more ingredients of different specific gravity, as for instance, a mixture of dead oil of tar, creosote, and a zinc chlorid solution, considerable difficulty is experienced in preventing the liquid mixture breaking down and separating into its component ingredients, and it is the purpose of my invention to provide an apparatus which will attain and maintain this perfect mixture or emulsion of the several ingredients of different specific gravities making up the impregnating liquid during the entire period of absorption and penetration.

The liquid supply tank 1 which is designed to contain the supply of liquid which is being constantly circulated through the impregnating cylinder 2 during the operation of treating timbers therein, has a suitable agitator located therein to keep the supply liquid constantly agitated and mixed to a homogeneous emulsion. This agitator may be of any desired form but in the present instance is illustrated as an air-supply pipe 3 which is run to the bottom of the liquid supply tank 1 and is extended along the bottom where it is provided with the perforations 4 which permit the air supplied therethrough to pass up through the liquid and disturb the ingredients of the heaviest specific gravity which will have settled to the bottom of this tank and to cause these ingredients to be moved in an upward current through the ingredients of a lower specific gravity which have a tendency to rise to the top of the solution.

The impregnating cylinder 2 may be made

of any desired form and dimensions, this cylinder being provided with one open end, and a door 5 adapted to be closed over this open end and held liquid and air tight by the securing clamp 6. A filling and return pipe 7 connects with the bottom of the liquid supply tank 1 and at its opposite end is connected at a point low down on the side of the impregnating cylinder 2, a suitable valve 8. 5
10 preferably of the gate type, being provided to control the opening through this pipe 7. This pipe 7 is intended only to accomplish the initial filling of the impregnating cylinder 2 after the timber to be treated has been placed therein and the door 5 has been secured in place, and to permit the return of the impregnating fluid from this cylinder when the treating action has ceased and it is desired to empty the cylinder so that the 15 door 5 can be opened to permit the removal of the treated timber and the placing of untreated timber in the cylinder to be impregnated.

A pressure pump 9 is installed as a part of 25 the apparatus, a pipe 10 extending from the lower part of the liquid supply tank 1 to the pump 9 and a pipe 11 being connected from the pump to the impregnating cylinder 2. It is preferable that the pipe 11 be 30 extended through the bottom of the cylinder 2 and that the branch discharge pipe 12 provided with the plurality of discharge openings 13 be connected with this pipe 11 to extend throughout the length of the cylinder 35 2 and thus insure an even discharge of liquid into all parts of the cylinder. The liquid outlet pipe 14 has a plurality of branches and these branches are each connected with the impregnating cylinder 2 in the upper 40 part thereof, an automatic pressure valve 15 is connected in the discharge from this outlet pipe 14 and a return pipe 16 is connected with the automatic-pressure valve 15 in such relation that the liquid passing there- 45 through is conducted and discharged into the liquid supply tank 1. A branch pipe 17 is connected between the outlet pipe 14 and the return pipe 16 through which the liquid may be circulated while the pressure is being 50 raised in the impregnating cylinder. A valve 18 which in the present instance is disclosed as of the manually operated type, but which might be governed and actuated by suitable automatic or mechanical control 55 means is located at any convenient point in the branch pipe 17 to permit control of the passage of the liquid through this pipe to gradually raise the pressure within the tank to a point where the automatic pressure 60 valve will operate, and it will be understood that by manipulation of the valve, the pipe may be left entirely open during the filling of the impregnating tank and may be gradually closed until the proper pressure is attained and thus no shock will be generated. 65

A pipe 20 controlled by the valve 19 is connected with the cylinder 2 at its one end and at opposite end is connected with the boiler supplying steam to the pump 9 or with any other suitable means to supply 70 steam therethrough to dry the sap and other moisture out of the pores of the wood preparatory to the impregnating process. A pipe 21 is connected with the upper side of cylinder 2 and a branch 22 of this pipe controlled by the valve 23 is connected with any suitable source of supply of compressed air, a second branch pipe 24 controlled by a valve 25 being connected with a vacuum pump or other suitable means to extract the 80 moisture, air, and steam from the impregnating cylinder 2 just prior to the introduction of the impregnating liquid thereinto.

The pressure valve, as better shown in Fig. 3, comprises the case 15' which has 85 the valve proper 26 mounted therein between the connection with the pipe 14 provided to form an outlet from the impregnating cylinder 2 and the pipe 16 which returns to the liquid supply tank 1, and a 90 spring 27 is provided to bear against this valve 26 to exert a pressure to oppose the opening of this valve and consequently to oppose the passage of liquid from the outlet pipe 14 to the return pipe 16. I have 95 illustrated the spring 27 as a simple coil spring placed around the stem of the valve 26 to bear against the reverse side of the valve and against the head of the case 15'. It will be understood that by changing this 100 spring and substituting therefor a spring of a greater or less stiffness, the valve 26 can be regulated to open at varying pressures, also in some instances it may be found desirable to provide means whereby the tension of this spring 27 may be adjusted and the valve can then be set to accommodate various operating conditions without the necessity of dismantling the parts to insert a new spring. 105

In operation the wood, ties, poles, lumber, etc., is loaded on trucks and run into the impregnating cylinder or otherwise placed therein and the door 5 is closed into place and is secured to make the cylinder air and 115 liquid tight. The valve 19 is opened to permit the passage of steam preferably dry steam, through the pipe 20 to fill the impregnating cylinder 2 and the wood is steamed a sufficient length of time to cause 120 the moisture and sap contained in the pores and cells thereof to be evaporated out into the atmosphere of the impregnating cylinder. When a sufficient amount of the moisture contained in the wood has been evaporated out, the valve 19 is again closed to 125 shut off the supply of steam, and valve 25 in the pipe 24 which leads to the vacuum pump, not shown, is opened, thus permitting the air, moisture, and steam within the cyl- 130

inder 2 to be exhausted through the pipe 21 connected therewith. This operation extracts the air and the remaining moisture from the wood leaving the cells and pores open, and in proper condition to absorb the preserving liquid. After a vacuum equal to from twenty-two to twenty-seven inches of mercury has been maintained in the interior 5 of the cylinder 2 for, under ordinary working conditions, from forty minutes to one hour, the valve 8 in the pipe 7 is then opened and the liquid flows from the liquid supply tank 1 into the exhausted impregnating cylinder 2 to entirely fill this cylinder and completely 10 submerge the wood contained therein to be treated. The valve 25 in the pipe 24 is now closed to cut off communication from the vacuum pump, valve 8 is closed to cut off communication from the liquid supply tank 1 to the impregnating cylinder 2 through the pipe 7. The valve 18 in the pipe 17 is opened to almost the full extent, the pump 9 is started, and liquid under pressure is supplied to the cylinder and is caused 15 to flow through the pipe 17. The valve 18 is set so that at the commencement, substantially the full quantity of liquid supplied to the chamber may discharge therethrough and this valve is then gradually closed down 20 until the passage through the pipe 17 is entirely cut off. This pump 9 takes liquid through the pipe 10 from the liquid supply tank 1 and then forces it through the pipe 11 under pressure to the impregnating cylinder 25 2, and as the cylinder 2 has been filled with liquid through the pipe 7, the further supply of liquid thereto through the pipe 11 causes the pressure to be proportionately increased. The liquid finds its way through 30 the several branches of the pipe 14 to the automatic pressure valve and by exerting a pressure against the valve 26 thereof overcomes the tension of the spring 27 causes this valve to be unseated and permits the 35 flow of liquid from the outlet pipe 14 through the return pipe 16 to the operating tank 1, there to be again, by the agitating air, thoroughly emulsified into a homogeneous preserving liquid to be again drawn 40 through the pipe 10 by the action of the pressure pump 9 and thence pass through the pipe 11 to be circulated to the impregnating cylinder 2 around the wood to be treated. This operation is continued for 45 perhaps from two to eight hours, depending on the quality and condition of the wood to be treated, until the proper impregnation has taken place, then the pump is stopped, valve 8 is opened, and by opening 50 valve 23 in the pipe 22 compressed air is supplied to the impregnating cylinder 2 to force the treating liquid back through the pipe 7 to discharge into the liquid supply tank 1. When the fluid has been entirely discharged 55 60 from the impregnating cylinder 2, the valve

8 will be again closed and the liquid will be retained in the liquid supply tank 1, the door 5 can then be released from its closed position and the treated wood removed from the cylinder and untreated wood placed 70 therein to be impregnated after which the operation is repeated as hereinbefore set forth.

From the foregoing it will be seen that I have provided an apparatus to be used to 75 impregnate wood with a preservative liquid, so arranged that an impregnating liquid comprising several immiscible ingredients of differing specific gravity may be used, and the liquid will be maintained in a perfectly 80 emulsified and homogeneous state. Further as it is impracticable with the present method to obtain a perfect vacuum within the impregnating chamber and to withdraw all of the air from the cells of the wood, a certain percentage of air will be retained within the impregnating cylinder and also in the pores of the wood, and as this air is forced 85 out by the supply of impregnating liquid to the cylinder and the penetration of the same into the pores of the wood, this air will not be retained in the impregnating chamber, but is permitted to pass freely from the impregnating chamber back to the operating tank and there performs a useful 90 95 operation in agitating the liquid contained within this liquid supply tank and that discharged from the impregnating cylinder through the return pipe.

It will be understood that slight changes 100 might be made in the form and arrangement of the several parts without departing from the spirit and scope of my invention, and hence I do not wish to be limited thereto except for such limitations as the claims 105 may import.

I claim:—

1. A wood impregnating apparatus comprising an impregnating cylinder, a source of supply of impregnating liquid, means to cause a constant supply and circulation of impregnating liquid through said cylinder, an outlet from the impregnating cylinder led to the source of supply, and means to maintain a constant and predetermined pressure of the impregnating liquid as circulated through said cylinder. 110

2. A wood impregnating apparatus comprising an impregnating cylinder, a liquid-supply tank, a supply pipe from the liquid-supply tank to the impregnating cylinder, a return pipe from the impregnating cylinder to empty into the liquid-supply tank, means to cause a constant circulation of liquid under pressure through the impregnating cylinder, and means to maintain a constant and predetermined pressure of the impregnating liquid as circulated through said cylinder. 115 120

3. A wood impregnating apparatus com- 130

prising an impregnating cylinder, a liquid supply tank, a supply pipe from the liquid-supply tank to the impregnating cylinder, a return pipe from the impregnating cylinder to empty into the liquid-supply tank, means mounted in the return pipe to impede the free passage of liquid therethrough, and means connected in the supply pipe to pass the liquid therethrough under pressure and 10 to cause a circulation through the return pipe.

4. A wood impregnating apparatus comprising an impregnating cylinder, a liquid-supply tank, a liquid supply pipe connected 15 between the liquid-supply tank and the impregnating cylinder, a liquid return pipe connected from the impregnating cylinder to discharge into the liquid-supply tank, a pressure pump located in the supply pipe 20 to cause the liquid to be discharged to the impregnating cylinder under pressure, and a valve arranged in the return pipe to maintain the pressure of the liquid within the impregnating cylinder and to permit circulation 25 of the liquid through this pipe.

5. A wood impregnating apparatus comprising an impregnating cylinder, a liquid-supply tank, supply and return pipes connecting these two members, a pipe to supply a fluid to evaporate the moisture from the wood when placed in the impregnating cylinder, a pipe through which the moisture and air contained in this cylinder are exhausted, a pump connected in the pipe from the liquid-supply tank to the impregnating cylinder to cause the impregnating liquid to be discharged into the impregnating cylinder under pressure, and means located in the return pipe from the impregnating cylinder to the operating tank to maintain the pressure of the liquid within the impregnating cylinder and to permit the circulation through this return pipe.

In testimony whereof I affix my signature in presence of two witnesses.

WILLIAM A. CECIL.
